UNITED STATES PATENT OFFICE.

JOHN S. SANSON AND WM. P. FARRAND, OF PHILADELPHIA, PENNSYLVANIA.

MACHINE FOR MAKING METALLIC SLATS FOR BLINDS.

Specification of Letters Patent No. 16,250, dated December 16, 1856.

To all whom it may concern:

Be it known that we, JOHN S. SANSON and WILLIAM P. FARRAND, of the city and county of Philadelphia and State of Pennsylvania, have invented a new and useful Improvement in Machinery for Making Slats for Window-Blinds; and we do hereby declare that the following is a full, clear, and exact description of the construction and operation of the same, reference being had to the annexed drawing, forming part of this specification, in which—

Figure 1 is a top view of the machine. Fig. 2 is a side elevation of the same. Fig. 15 3 is an end view.

Similar characters of reference in the several figures denote the same part of the machine.

The usual practice in making slats for revolving iron shutters, has been to cut the slats from the sheet previous to giving them their final shape, which is attended with many difficulties such as the springing of the slats edgewise, caused by the lengthening of the iron from the action of the cutter, and to correct which, involves much labor and expense. The shaping or corrugation of the slats has been accomplished by the use of dies and swages which is a slow and 20 laborious process and is liable to cover the work with indentations and also to crook the edges by irregular stretching from the dies acting upon a portion of the surface only, at one time. Shaping has also been 25 accomplished by pressure, but not with satisfactory results, it being practically impossible to arrange the shape of the bed die, to suit the elasticity of the different sheets of iron, consequently producing no uniformity in the shape of the slats, without heat 30 is employed to destroy the elasticity of the iron.

The nature of our invention by which the above defects are remedied, consists in 35 structuring the machine with a bed and drop beam of the form to give the slat its shape, and in combining a shear with the drop beam so that the face of the beam will act to corrugate the iron simultaneously with 40 the cutting of the finished slat from the

sheet. The details of construction and operation are as follows.

In the drawing B is the bed formed to give the proper shape to the slat, and B' is the drop beam whose under surface corresponds in shape with the face of the bed. This beam is hinged to the bed at *a*; and has on its front end a rack *b*, so that it may be lifted by the gearing *G*. When it is elevated the segment *c* leaves the rack *b* and 55 the beam drops. The edges *m* and *n* of the bed and beam constitute a shear for cutting the slat from the sheet. Within the bed is a series of stops *f* each lifted by a spring *e* when the beam is raised. These 60 give the width of the slat. As the beam falls these stops are driven into the bed, and are held in that position by the points *i* on plate *l* pressing against them by the force 65 of springs *g*. As the beam reaches its greatest elevation the plate *l* is drawn longitudinally by the lever *d*, releasing the stops and permitting their springs to lift them. The sheet is run upon the bed until arrested by the stops, then the descent of 70 the beam gives the form to the slat, and separates it from the sheet; the corrugating 75 taking place slightly in advance of the shear cut.

By the use of a drop beam with the face 80 to correspond with shape of slat, and hinged at one end, we combine power and speed with the least amount of material, the leverage of the beam giving the power at the hinged end, and the momentum from its accelerated speed at the outer end. And being free from connections in dropping, it 85 exerts the same concussive force and adapts itself to the usual variations, in the thickness 90 of the iron.

By combining the shear with the drop beam, arranged in such manner that the face of the beam acts or corrugates the iron, in advance of the cutter, additional stiffness 95 is given to the iron, increasing the resistance against springing through the action of the shear, thereby producing straight slats; and which entirely dispenses with the expense and inconvenience attending cutting as a separate process, it being accomplished si- 100

multaneously with corrugating, and also reduces the expense of the cutting apparatus considerably.

We claim—

5. The combination of bed, beam and shear with the spring stops, constructed arranged and operating substantially as and for the purposes set forth.

In testimony whereof, we have hereunto signed our names before two subscribing 10 witnesses.

JOHN S. SANSON.
W. P. FARRAND.
